SEWING MACHINE

Bernard A. Schmitt, Chicago, Ill.

Application November 14, 1945, Serial No. 628,561

8 Claims. (Cl. 112—191)

1

This invention relates to sewing machines, and more particularly to sewing machines of the household or domestic type.

It is a general object of the present invention to provide a novel and improved household sewing machine.

More particularly it is an object of the invention to provide in a household type sewing machine improvements in the construction and arrangement of the essential parts and drives which contribute to simplicity of manufacture and maintenance and materially reduce the noise of operation.

Among the important objects of the invention is the arrangement of the stitch adjusting mechanism for drives by a constant velocity vertical shaft whereby simplification of the manual adjusting mechanism is effected.

A further object of the invention comprises the arrangement in a sewing machine of stitch forming mechanism beneath the bed plate and constructed for rotation about a vertical axis, together with a drive for the same which also serves to provide a simplified motion for the cloth feeding and stitch adjusting mechanism.

Another important feature of the invention resides in the arrangement of substantially all of the operating mechanism beneath the bed plate where it is readily available for lubrication and adjustment and yet is easily protected against injury to the operator or to curious children who might investigate the machine while in use.

Other and further objects and features of the invention will be more apparent to those skilled in the art upon a consideration of the accompanying drawings and following specification, wherein is disclosed a single exemplary embodiment of the invention, with the understanding that such changes may be made therein as fall within the scope of the appended claims without departing from the spirit of the invention.

In said drawings:

Fig. 1 is a front elevation of a sewing machine constructed in accordance with the present invention with portions of the bed plate and standard broken away to more clearly illustrate the drive mechanism;

Fig. 2 is a bottom plan view of the construction of Fig. 1;

Fig. 3 is an end elevation showing portions of the standard in section to illustrate the mounting of the vertical drive shaft;

Fig. 4 is a fore and aft section on line 4—4 of Fig. 1, showing the intermediate guide and fulcrum for the shuttle drive and connecting rod;

2

Fig. 5 is a section taken on line 5—5 of Fig. 2 showing the sliding block and shuttle crank arm where it is connected to the shuttle drive connecting rod; and

Fig. 6 is an exploded view of the ball joint connection between the cloth feed connecting rod and the oscillatable feed shaft.

Sewing machines at present on the market for the household trade, while reasonably satisfactory in operation, are costly and inclined to be noisy. They have certain undesirable operating characteristics and it is the intention of the present invention to so simplify the construction of such machines as to reduce the amount of machine work in the manufacture of the same, and so assemble the parts that they are readily available when there is need for lubrication or adjustment and to eliminate many sources of noise whereby the objectionable clatter of the usual machine is materially reduced.

Referring now to the drawings, it will be seen that in general outline the sewing machine of the present invention conforms to the conventional. It is provided with a suitable bed plate 10 which 15 may be a casting provided with legs 12 and flanges 13 for standing and reinforcing the same. The usual standard 15 extends upwardly from the right end of the bed plate and has formed integrally therewith the arm 16 supporting the head 18. This head is equipped with the usual needle bar 20 and other conventional parts, such as thread takeup, presser foot and the like, which form no part of the present invention.

The stitch forming mechanism, not shown in detail, includes a rotary hook or shuttle mechanism 22 adapted to be rotated by a supporting vertical shaft 24 carried and journaled in a bracket 26 suitably secured to the lower surface of the bed plate. It will be noted that the left hand side of the shuttle mechanism is in alignment with the needle whereby the whole of the bobbin carrying portion is available from the right hand side of the needle through a suitable assembly cover, not shown, which permits the operator 35 to remove and replace the bobbin entirely with the right hand. This is a much more favorable arrangement than the conventional machines which require left hand operation and have the shuttle and bobbin so arranged they are not readily visible.

In keeping with conventional sewing machines, the present one is equipped with a main or drive shaft 30 extending through the standard, the arm and into the head, at which head end it is 45 equipped with the necessary mechanism for driv-

ing the needle bar, thread takeup and the like. In order to drive the shuttle shaft 24 power is delivered from the main shaft to a position beneath the bed plate by means of vertical shaft 32 arranged within the standard and driven from the main shaft by a set of one-to-one ratio helical gears 34. As seen in Fig. 3 the vertical shaft is in front of the main shaft and is journaled near its two ends in extensions 36 and 37 of the bracket member 38, which is secured by means of bolts 39 firmly against projecting bosses 40 on the inner wall of the standard. Slight fore and aft adjustment to provide for depth of gear meshing and the like is available at both ends of the bracket 38 because of the enlargement of the holes therein through which the studs 39 pass. These studs can be loosened slightly to permit adjustment and then tightened to hold the same. This bracket member includes an integral lug 42 whose upper surface is slightly above the plane of the top of the bed plate.

The vertical shaft 32 is equipped at its lower end with a crank arm 45 to which the right end of connecting rod 46 is attached by means of a tapered pivot 47 adjustable in the arm 45 to take up wear. The connecting rod, which is generally of flat rectangular cross-section, is offset at 49 and receives at its left hand end a suitable pivot member 50 passing through a tapered sided block 51 slidable between the tapered inner faces of forked arms 52 of a crank 53 secured to the lower end of shuttle shaft 24.

A rotary stitch-forming mechanism of the hook or shuttle type which makes one revolution for each stroke of the needle must operate with a non-uniform rotary motion in order to travel at sufficiently slow speed when the needle passes through the bed plate to permit the proper engagement of the thread thereof by the hook mechanism. Such non-uniform rotary motion is imparted to the shaft 24 from the uniformly driven shaft 32 by the connecting rod arrangement just described, operating in conjunction with an intermediate guide and fulcrum 54, best seen in Fig. 4. The connecting rod 46 in that figure will be seen to have its edges converging slightly downwardly as at 55 and received in the guide member 54 having a correspondingly shaped recess. This guide member is of generally U-shaped configuration and is attached by suitable pins or rivets to a closure or head member 58 attached to a vertical shaft 59 journaled in a guide element 60 preferably of cylindrical configuration. The upper end of the shaft 59 is threaded and receives a nut which fits against the upper end of the guide 60. This permits oscillating motion of the part 54 which guides the connecting rod intermediate its ends and causes the end 50 thereof to travel in an oval path, one end of which is almost pointed. This movement imparted to the sliding block 51 results in a slow-up in the rotational speed of the shuttle at the time the needle is entering the bed plate. The remaining motion of the shuttle, effected largely when the block 51 is close to the shaft 44, is at much higher speed.

It will be noted that the connecting rod 46 does not bottom in guide 54. The space remaining is to permit adjustment for wear, which is effected by raising the guide member 60. This member is received in a socket 62 cast integral with the bed plate, drilled to be a close fit and split and provided with ears 63 adapted to be clamped by the screw shown to hold the guide 60 in any desired vertical position.

To feed cloth the sewing machine is provided with a conventional feed point and feed lever, not shown, adapted to be raised and lowered by any convenient mechanism and to have fore and aft motion of adjustable stroke length imparted thereto in any suitable manner from a feed shaft 70 journaled beneath the bed plate toward the rear thereof and parallel to the main shaft 30, as clearly seen. This shaft 70 is relatively remote from the vertical shaft 32 and motion is transmitted from the latter to the former through the agency of a substantially horizontally disposed connecting rod 72, the smaller end of which is equipped with a ball head 73 attached thereto by a reduced shank 74. This is adapted to be articulated universally to a substantially vertical arm 75 extending upwardly from the shaft 70, as best seen in Fig. 6. The portion 77 of this arm is removable and each section is provided with a semi-spherical recess 79 connected to the forward face by means of a passage 79. When the part 77 is engaged against the main part 75, the ball end of the connecting rod is closely housed and guided for operating the shaft 70. The part 77 is conveniently attached by means of pins 80 and a snap spring 81 engaging grooves 82 in the edges of the parts of the arm 75.

The other end of the connecting rod, instead of being forked which requires greater weight and strength, is substantially enlarged as at 85, and provided with a large opening which passes over or around the vertical shaft 32 and is provided with opposed cam followers 88 which cooperate 35 with an ovate outlined cam 86 mounted on the shaft above the crank. As seen this cam is tapered upwardly to a slight extent and is engaged by the flat follower faces 88 forming the axially disposed sides of the elongated opening in the enlarged head of the connecting rod. These faces taper the same as the cam to permit automatic takeup of wear as well as to provide for supporting the large end of the connecting rod on the cam.

Since the follower faces which engage the cam are parallel to the axis of the connecting rod, the cam would normally impart no longitudinal motion to the rod but would only move the head transversely. In order to permit a transfer of this transverse motion to longitudinal motion between zero and the maximum amount required to provide the longest stitch desired by the machine, movement of the large end of the connecting rod is controlled by a restraining link 90, one 50 end of which is pivotally attached by tapered stud 92 to an ear 91 which is arranged on the enlarged head of the connecting rod adjacent the inner end of one of the cam followers.

The opposite end of this link is attached to a fulcrum or pivot member 93, which is adapted to be adjusted and held at any position between those shown in full and dotted lines in Fig. 2. It will be seen that when the pivot 92 between the ear and the link 90 is so aligned with fulcrum 93 that a line passing through them is parallel to the axis of the connecting rod, that movement of the large end of the connecting rod is purely lateral and no oscillation is imparted to the feed shaft 70. As the fulcrum 93 is moved toward either the full or dotted line positions shown in Fig. 2, more and more of the lateral movement of the big end of the connecting rod is converted to longitudinal movement because of the increasing angularity between said line and rod axis. By 70 permitting the fulcrum to be moved to either side

of the parallel position the phase of the oscillation of the feed shaft can be adjusted in respect to the needle bar so that forward or backward stitching can be accomplished. The length of the stitch in either direction is adjusted by positioning the fulcrum 93 more or less in angular relationship to the said parallel line.

To control and limit the path of the fulcrum or pivot 93 it is carried by the free end of a link 96 in which it is mounted. The opposite end of the link is fixed by means of a suitable pivot 97 in the lug 42 on the bracket for shaft 32. It will be seen that all of the connections and pivots are of the tapered variety and arranged for adjustment to compensate for wear. The position of the pivot 97 is not greatly displaced from that of pivot 92 and the links 90 and 96 are of similar length, which will limit the movement of the fulcrum 93 to an arc whose center is substantially in the path of movement of pivot 92.

To accurately position and hold the fulcrum 93 for determining the length of stitch, it is provided with a pin extending from its upper end, as clearly seen in Figs. 1 and 3, which is received in a slot 98 in the inner end of a lever 99. This lever is pivoted intermediate its ends at 100 on an extension of lug 42. The outer or forward end 101 of the lever extends through a slot 102 in the forward face of the standard 15 and the pointed end sweeps over the surface of the bed plate, which may be suitably graduated to indicate stitch length and direction. The portion 99 of the lever is curved as shown, in order to clear intermediate parts when the whole thing is moved to the dotted line position shown for link 96. The fulcrum 100 for the operating lever is arranged to frictionally hold the same in any position to which it may be set.

I claim:

1. In a household type sewing machine, in combination, a bed plate, a standard thereon, an arm extending from the standard and supporting a head, a rotary main shaft extending through the standard and arm and into the head, a vertical shaft journalled for rotation in the standard, one-to-one ratio gears driving the vertical from the main shaft, a shuttle shaft journalled for rotation about a vertical axis beneath the bed plate, a crank on the vertical shaft beneath the bed plate, a crank on the shuttle shaft, a slide on one of said cranks, a connecting rod pivoted to one of the cranks and to said slide, an intermediate guide fulcrum for said rod, and means pivoting said guide beneath said bed plate.

2. In a household type sewing machine, in combination, a bed plate, a standard thereon, an arm extending from the standard and supporting a head, a rotary main shaft extending through the standard and arm and into the head, a vertical shaft journalled for rotation in the standard, one-to-one ratio gears driving the vertical from the main shaft, a shuttle shaft journalled for rotation about a vertical axis beneath the bed plate, a crank on the vertical shaft beneath the bed plate, a crank on the shuttle shaft, a slide on one of said cranks, a connecting rod pivoted to one of the cranks and to said slide, an intermediate guide fulcrum for said rod, means pivoting said guide beneath said bed plate, the sides of said connecting rod converging, the walls of said guide having a corresponding taper and means to vertically adjust the guide to compensate for wear.

3. In a sewing machine, in combination, a bed plate, a standard thereon, a rotary vertical shaft

extending within the standard and through the bed plate, a feed shaft pivoted for oscillation beneath the bed plate and spaced from the vertical shaft, an arm extending from said feed shaft and oscillatable therewith about a vertical position, a cam on the vertical shaft beneath the bed plate, a connecting rod universally pivoted to said arm, the opposite end of said connecting rod being enlarged to provide opposed followers adapted to engage the cam, said followers extending substantially parallel to the axis of the connecting rod, a restraining link for said connecting rod, a pivot attaching said link to the connecting rod near said followers, a floating pivot for the other end of said link and means to restrain said floating pivot for movement in an arc having its center adjacent the path of said first pivot.

4. In a sewing machine, in combination, a bed plate, a standard thereon, a rotary vertical shaft extending within the standard and through the bed plate, a feed shaft pivoted for oscillation beneath the bed plate and spaced from the vertical shaft, an arm extending from said feed shaft and oscillatable therewith about a vertical position, a cam on the vertical shaft beneath the bed plate, a connecting rod universally pivoted to said arm, the opposite end of said connecting rod being enlarged to provide opposed followers adapted to engage the cam, said followers extending substantially parallel to the axis of the connecting rod, a restraining link for said connecting rod, a pivot attaching said link to the connecting rod near said followers, a floating pivot for the other end of said link, a second link having one end pivoted to the said floating pivot and the other end pivoted to a fixed point which is substantially intersected by the path of a projection of the first pivot.

40 5. In a sewing machine, in combination, a bed plate, a standard thereon, a rotary vertical shaft extending within the standard and through the bed plate, a feed shaft pivoted for oscillation beneath the bed plate and spaced from the vertical shaft, an arm extending from said feed shaft and oscillatable therewith about a vertical position, a cam on the vertical shaft beneath the bed plate, a connecting rod universally pivoted to said arm, the opposite end of said connecting rod being enlarged to provide opposed followers adapted to engage the cam, said followers extending substantially parallel to the axis of the connecting rod, a restraining link for said connecting rod, a pivot attaching said link to the connecting rod near said followers, a floating pivot for the other end of said link, a second link having one end pivoted to the said floating pivot and the other end pivoted to a fixed point which is substantially intersected by the path of a projection of the first pivot, an operating lever extending through the front wall of said standard above the bed plate, said lever having an intermediate pivot within said standard, and means connecting the inner end of said lever to said floating pivot for positioning the same to regulate the stroke of said connecting rod and hence of said feed shaft.

6. In a sewing machine, in combination, a bed plate, a standard thereon, an arm extending from the standard and supporting a head, a rotary main shaft extending through the standard and arm and into the head to drive a needle bar, a shaft geared for one-to-one operation from the main shaft, a bracket having journals for said second shaft, means mounting said bracket in 70 said standard with the shaft extending vertically,

a crank on said shaft beneath said bed plate, a stitch forming mechanism adapted to cooperate with the needle and including a bobbin-carrier, a vertical shaft for the latter, a bracket supporting and journaling said shaft from the bed plate, a crank arm on the bottom of said last mentioned shaft, a slider mounted on said crank arm, a connecting rod pivoted at its opposite ends to said crank and to said slider, an intermediate guide and fulcrum for said connecting rod, a mounting block journaling said guide and a clamping socket integral with said bed plate to adjustably hold said mounting.

7. In a sewing machine, in combination, a bed plate, a standard thereon, an arm extending from the standard and supporting a head, a rotary main shaft extending through the standard and arm and into the head to drive a needle bar, a shaft geared for one-to-one operation from the main shaft, a bracket having journals for said second shaft, means mounting said bracket in said standard with the shaft extending vertically, a cam on said shaft beneath the bed plate, a connecting rod having parallel axially disposed followers engaging said cam and adapted to actuate a feed shaft, a restraining link pivoted to said rod near one of said followers, a second link having one end pivoted to the free end of the first link, a lug on said bracket, and a pivot for the other end of the second link secured to said lug.

8. In a sewing machine, in combination, a bed plate, a standard thereon, an arm extending from the standard and supporting a head, a rotary main shaft extending through the standard and arm and into the head to drive a needle bar, a 35

shaft geared for one-to-one operation from the main shaft, a bracket having journals for said second shaft, means mounting said bracket in said standard with the shaft extending vertically, 5 a cam on said shaft beneath the bed plate, a connecting rod having opposed parallel followers engaging said cam in planes parallel to the rod axis and adapted to actuate a feed shaft, a restraining link pivoted to said rod near one of said followers, 10 a second link having one end pivoted to the free end of the first link, a lug on said bracket, a pivot for the other end of the second link secured to said lug, a second lug on said bracket, a lever pivoted intermediate its ends on said second 15 bracket and having a portion extending through a slot in the front wall of said standard, a second portion having a slot and means on the pivot connecting the two links engaged by the walls of the slot for positioning thereby.
